Primary Examiner — Susan E Krakower*Assistant Examiner* — Jerry Shiuan-Hua Hsu(74) *Attorney, Agent, or Firm* — Avery Dennison Retail Information Services, LLC(57) **CLAIM**

The ornamental design for an antenna, as shown and described.

DESCRIPTION

FIG. 1 is an isometric view of the antenna, showing my new design; and,

FIG. 2 is a top view thereof.

The broken lines illustrate portions of the antenna that form no part of the claimed design.

1 Claim, 2 Drawing Sheets(56)
